CLAIM

The ornamental design for an animal training device, as shown and described.

DESCRIPTION

FIG. 1 is a front perspective view of an animal training device;

FIG. 2 is a front elevational view thereof;

FIG. 3 is a rear elevational view thereof;

FIG. 4 is a left side elevational view thereof;

FIG. 5 is a right side elevational view thereof,

FIG. 6 is a top plan view thereof;

FIG. 7 is a bottom plan view thereof, and,

FIG. 8 is a front perspective view of the invention of FIG. 1 shown with the environment.

In the drawings, the broken line showing of a dog collar depicts environmental subject matter and forms no part of the claim.
